UNITED STATES PATENT OFFICE.

DAVID S. WERT, OF PITTSBURG, PENNSYLVANIA.

RAIL-CLAMP.

942,427.

Specification of Letters Patent.

Patented Dec. 7, 1909.

Application filed March 5, 1909. Serial No. 481,244.

To all whom it may concern:

Be it known that I, DAVID S. WERT, citizen of the United States, residing at Pittsburgh, in the county of Allegheny and State 5 of Pennsylvania, have invented certain new and useful Improvements in Rail-Clamps, of which the following is a specification.

This invention comprehends certain new and useful improvements in rail fasteners, 10 and relates particularly to an improved clamp designed to secure the rail to the tie.

The invention has for its object a simple, durable and efficient construction of rail clamp which may be cheaply and easily 15 manufactured and which may be readily applied to any of the accepted types of metallic ties to securely and rigidly hold the rail thereon, and the invention consists in certain constructions and arrangements of the 20 parts that I shall hereinafter fully describe and claim.

For a full understanding of the invention and the merits thereof, and to acquire a knowledge of the details of construction, 25 reference is to be had to the following description and accompanying drawing, in which:

Figure 1 is a top plan view of portions of two rails, illustrating my improved rail 30 clamp in applied position; Fig. 2 is a transverse longitudinal sectional view, the section being taken substantially on the line 2—2 of Fig. 1. Figs. 3 and 4 are enlarged sections illustrating different adjustments of 35 which the clamps are capable; and, Fig. 5 is a detail perspective view of one of the clamps.

Corresponding and like parts are referred to in the following description and indicated in all the views of the drawing by the 40 same reference characters.

Referring to the drawing, the numeral 1 designates the bed or top portion of a metallic railway tie which may be of any desired 45 construction or design, so far as its general character is concerned; that is to say, my invention is applicable to metallic ties of different cross sectional contour, such as I beams, T beams, or channeled or boxed constructions.

2 designates the base flanges of the rails.

The tie 1 is formed on opposite sides of each rail with preferably punched-out 50 openings 3 extending therethrough, the walls 55 of said openings being preferably downwardly flared or beveled, and the opposing

portions of said walls being spaced from each other a distance somewhat less than the width of the superposed rail base. In addition to these openings 3, the tie 1 is also 60 formed with apertures 4 spaced from and in longitudinal alinement with adjacent openings 3, the said openings 3, as will be best seen by reference to Fig. 1, being disposed in offset relation to each other. 65

5 designates my improved clamp which may be formed out of any suitable metal or material, although preferably constructed of relatively soft wrought steel. It is to be understood that these clamps may be produced by any desired process, and be formed by any desired method of manufacture. Each clamp embodies a head portion 6, a relatively long neck portion 7, and an attaching arm 9. The head 6 has its face edge 75 10 curved to correspond to the curvature of the rail flange, but on a larger radius, in order to provide for the proper adjustment, and the rear edge of the head describes an angle with the upper edge of the neck 7, the apex 11 of which constitutes a fulcrum point. Preferably the rear edge of the head 6 is defined by a straight line, a distance upwardly from the fulcrum point 11 at least 80 equal to the thickness of the bed or top portion of the tie through which the openings 3 are formed. The attaching arm 9 which projects upwardly at an angle to the neck 7, is preferably longitudinally split along its median line from its upper end to a point 90 near its base or juncture with the outer end of the elongated neck, as indicated at 12.

In the practical use of my improved rail clamp, the rail is first placed in alinement over and between corresponding openings 95 3, and one of the clamps 5, say the inside clamp, is inserted partially through its opening and engaged with the adjacent base flange, care being taken to draw the tie so that the rear edge of the head 6 will engage the full extent of the beveled opening wall with the fulcrum point 11 abutting against the lower edge of such wall. In this position, it is evident that the attaching arm 9 of this clamp projects upwardly 100 through the adjacent aperture 4 and is bent either as a whole in one direction or the other to engage with the top surface of the tie, or the split portions may be bent in opposite directions to effect such engagement, 105 as clearly illustrated in the drawing. The opposite clamp for the same rail is then 110

5 applied, and tension is exerted thereon, forcing this last named clamp to rock about the point 11 as a fulcrum until the desired tension has been obtained, the face edge of the head extending downwardly into locking contact with the adjacent base flange. This relative arrangement of the parts is illustrated in Fig. 3.

10 It is clear that the ideal arrangement is one wherein the rear edges of the heads of both clamps of a pair of clamps engage with the adjacent walls of the openings the full thickness of the top of the tie, as illustrated in Fig. 2; but it is also clear to those versed 15 in the art to which this invention appertains, that this arrangement cannot always be carried out, owing to slight variations in the ties and rails, and also where it is necessary to slightly vary the gage.

20 As an example of the use of my improved clamps in changing the gage of a track, reference is to be particularly had to Figs. 3 and 4. By reference to these last named views, in connection with the foregoing description, it will be understood that by rocking one of the clamps about the fulcrum point 11 as an axis, in a direction to raise the point *a* of the clamp, and by rocking the opposite clamp in the opposite direction 25 to lower its point *b*, the rail may be forced to the extreme right, as illustrated in Fig. 3. Conversely, by lowering the point *a* of one clamp, and raising the point *b* of the complementary clamp, the rail is forced to 30 the extreme left.

35 From the foregoing description, in connection with the accompanying drawing, it will be seen that I have provided a very simple and durable construction of rail 40 clamp which will securely hold the rails to the ties, after being once applied, and which may be easily secured in properly adjusted positions, the clamps acting upon the principle of levers with the fulcrum points at

11 the short arms being constituted by the 45 head, and the longer arms by the neck portions, so that a maximum tension may be placed upon the rail against the tie, commensurate with the strength or tenacity of the material out of which the clamps are 50 formed.

Having thus described the invention, what I claim is:—

The combination with a tie formed with 55 openings extending therethrough and designed to lie underneath and at opposite sides of a superposed rail base, the said openings being downwardly flared, the tie being also formed with apertures spaced from said openings on opposite sides of a 60 rail, a rail resting on the ties between and over the opening, and clamps arranged to secure the rail to the tie, said clamps embodying heads projecting upwardly through 65 the openings and formed with face edges 70 curved correspondingly to the side edges of the base flanges, but on a larger radius, neck portions extending outwardly in opposite directions from the rail and underneath the tie and angularly disposed to the head portions, and upwardly extending attaching 75 arms projected upwardly through the said apertures and arranged for adjustable fastening therein, the point of juncture between the rear edges of the heads and the 80 upper edges of the neck portions constituting fulcrum points engaging the outer walls of the openings at the lower edges thereof and the rear edges of the heads being straight or plane from said fulcrum points 85 and upwardly a distance at least equal to the height of the walls of said opening.

In testimony whereof I affix my signature in presence of two witnesses.

DAVID S. WERT. [L. S.]
